FIG. 11.

UNITED STATES PATENT OFFICE.

JOHN H. FLATLEY, OF LITTLE YORK, ILLINOIS.

SCRAPER FOR HARROW DISKS AND MEANS FOR OPERATING THE SAME.

Application filed June 16, 1924. Serial No. 730,239.

My invention relates to improvements in disk harrows. More particularly, the invention pertains to improvements in scrapers for harrow disks and to mechanism for operating the same.

One of the objects of my invention is to produce a scraper of a peculiarly different form from any of which I am aware. Further, to present a working edge thereof to the disk-surface in an entirely different manner and in such manner that said disk can be readily and properly cleaned under any conditions that may exist.

Another object is that in presenting the scraper to its work the dirt will be removed progressively from a point nearest the center of disk-rotation, for example, toward the perimeter of the disk to the end that the draft upon the implement will not be suddenly increased. That is to say, rather than force a set of the scrapers into the entire bulk of the adhering matter on a series of disks, and thus suddenly increase the draft, it is my purpose to so construct the scrapers that a gradual removal will take place, the material being removed in a spiral cut until all is removed. But this will be made clear in the description to follow.

Still another object is to provide for maintaining the scrapers in yielding contact with the disks and to employ a flexible member for each scraper adjustable with respect to a common operating member controlling a series of such scrapers.

A still further object is to furnish a mechanism for controlling all of the scrapers wherein sets of the latter may be selectively presented to the disks.

The appended drawings illustrate my invention in its preferred form though it is to be understood that the structures shown are susceptible of changes such as may be considered to lie within the invention and within the scope of the claims herein.

Figure 1 is a plan of a disk harrow showing my invention applied thereto.

Figure 2 is a rear elevation of a scraper of my invention showing its convex side.

Figure 3 is a side elevation of the scraper as seen from its concave side.

Figure 4 is a front elevation of the same showing its concave form.

Figure 5 shows the scraper in perspective view at its front supported edge.

Figure 6 is a side elevation of a portion of a harrow disk showing the location of a scraper with respect thereto.

Figure 7 shows a portion of a disk as viewed from above, a second disk in horizontal section, and a scraper showing its possible positions with respect to both disks.

Figure 7^a is a section of part of a disk and scraper taken on line 7^a, Figure 6.

Figure 8 is a plan in detail of parts shown in Figure 1.

Figure 9 is a rear elevation of the same.

Figure 10 shows, in perspective, certain parts shown in the last two figures. Figure 11 is a plan of a modified form of scraper operating mechanism, and Figure 12 is a detail of the same.

Before entering upon a detailed description of my invention it may be stated that heretofore scrapers have been constructed and mounted so as to present their edges to the faces of the disks after the manner of a chisel, i. e., the scraper-blade lying at an acute angle to the plane of disk-rotation, with the idea of cutting into the adhering matter. But under all conditions of soil this method of removal has not been found to answer. Experience has shown that the dirt under some conditions will accumulate or build up between the scrapers and disks forcing the former away from working contact. Again, when a scraper of the common type is new there is a sharp edge or corner in contact with the disk which cleans properly under ideal soil conditions. However, since the scraper body lies at an acute angle to the disk-surface said edge or corner is finally worn to a bevel and simulates a chisel-end whereupon it fails to properly function since there is then no abrupt corner to act as a scraper should. When this condition obtains, the operator must remove all of the scrapers and restore their edges to the condition when first applied.

It is my purpose, in view of the above, to so construct a scraper and to so present it to the disk that a clean scraping action will be maintained indefinitely without attention. This, however, will be made clear as the description proceeds, including other advantages of my invention.

The numeral 1 designates the main frame of a disk harrow, 2 the tongue or draft-member, while 3 and 4 indicate certain members

below which are located disk-gangs 5 journaled in any usual and well known manner, the carrying wheels being denoted at 6. To these parts I attach no claim, however, of themselves, since they are shown merely to make the application of my invention clear.

Journalized in an upright position in the members 3, for example, as clearly shown in Figures 3, 8 and 9 are the stems or shafts 7 of scraper-blades 8, figures 2 to 7 inclusive, such stems or shafts being disposed between the several disks 9 in the positions most convenient for the required operation. Said blades are properly rights and lefts in order to engage the concave surfaces of the disks of the gangs as placed.

The form of the scrapers is illustrated in the several figures, 2 to 7 inclusive, the general outline being made clear in Figure 3. One edge is securely bolted to the stem 7 while an opposite edge 11, before the blade is bent into the form shown, and to be described, is substantially parallel to the bolted edge. The top edge 10 is slightly curved 25 from the stem 7 as shown in plan in Figure 7 and continues into the edge 11, the latter being the actual working edge to have contact with the disk. It is noted that said edge 11, Figures 2 and 5 is spirally formed, the general line of which lies at an angle to the axis of the stem as viewed in planes at right angles to each other and at an angle, therefore, to the axis of swinging movement 30 of the blade. The general form of the scraper-blade may be likened to a longitudinal section of a hollow cone since it is bent from a small curve at 12, Figure 3, such curve gradually spreading to longer curves as denoted by the shade lines in said figure. 35 This is with the whole purpose of creating the spiral edge 11 presented to the disk-surface in the position shown. The face of the blade lies at right angles to the said disk-surface as shown in Figure 7^a, the edge 11 lying squarely upon such surface, the arrow in this figure showing or indicating the direction of disk-rotation. Clearly, the wear of the disk on the scraper is at right angles to what may be termed the plane of the 40 scraper and the edge 11 never changes its form, the proper scraping action being maintained indefinitely. In presenting the edge 11 to the disk the lower corner of said edge first engages the adhering matter 45 nearest the disk center and in a continued movement toward a full contact progressively removes the material in a spiral cut outward toward the perimeter of the disk, this progressive engagement of the scraping edge 50 with the disk surface is due primarily to the shape of the scraper, the angle of the edge 11 with respect to the disk surface and pivotal mounting of the blade, and the manner in which the scraper is moved into engagement with the disk. As shown in Fig. 55

7, it will be apparent that movement of the scraper about axis 7 will cause that portion of edge 11 which is adjacent edge 12 to first engage the central portion of the scraper disk. Continued movement of the scraper about axis 7 will cause said edge portion to move to a position obliquely across the disc surface and progressively engage the entire edge 11 therewith. The advantage of this action is that when an entire series of scrapers is moved to scraping position the entire load of material is not suddenly attacked, since to do so, especially when the soil is of a sticky or gummy nature, would greatly increase the draft on the implement. 80

The form of the scraper and the position in which it may be mounted is advantageous in that, as shown in Figure 7, the edge 11 can be made to engage the outer or convex surface of an adjacent disk and remove the dirt from that part of said surface that prevents proper functioning of said disk in the soil. The dotted lines *a a* in said Figure 7 designates substantially the zone of scraping action. The position of the stem 7 between the disks may vary according to the form of the scraper and its ability to serve in both the capacities named. 90

There is included with the several scrapers a control mechanism by which I am enabled, preferably, to operate certain sets or series of said scrapers, the others being allowed to remain idle. To this end there is journaled upon the tongue or draft device 2 a rock-shaft 13. This lies along said tongue and has a pair of upstanding arms 14 and 15 disposed somewhat in the rear of the positions of the gangs 5. 95

Secured to the upper end of each stem 7 is an arm 16 preferably capable of flexing and may be made, therefore, of spring metal. These lie substantially parallel to one another, having reference, of course, to those of a given series, and each is pivotally connected to a bar 17. Connected to said bar by a pivot bolt 17', for example, is a link 17² one end of which is slotted to receive one of the arms 14, 15. At the point of pivotal connection of the arm 16 with the bar 17 the latter is slotted as at 18, Figure 8, whereby an adjustment of the said arm may be made with respect to such bar. By a study of Figure 1 it will be seen that two of the bars are controlled by each of the arms 14, 15 of the rock-shaft. As arranged, it is clear that if the rod 13 is rocked so as to swing the arms 14, 15 toward the right, for example, the left front bar 17 and the right rear bar 17 will both be shifted toward the right, the other two bars 17 being unaffected. Similarly, in the movement of the said rod 13 to swing the said arms 14, 15 toward the left the right forward and the left rearward bars 17 will be operated without movement of the other two. In use, all of the scrapers are prefer- 100 105 110 115 120 125 130

ably kept free of the disks, though, of course, this need not be followed necessarily. However, if normally out of contact and it is necessary to clean the disks it is preferable to 5 operate two of the series of scrapers at a time only. That is to say, the front series at the right may be engaged with their disks together with the left series at the rear. Following this the forward series at the left and 10 the right series at the rear may be operated. This is done in order that a too heavy draft will not be placed suddenly upon the power, and further, that thus applied there will be no tendency to sidewise movement of the implement. And, again, the operation is simplified and added mechanism is not required. The links 17² are so placed with respect to the arms 14, 15, and to each other, that when the rock-shaft is moved in one direction the 15 two series of scrapers first named, for example, may be actuated, while an opposite direction of movement will affect the other two series. And an extreme movement in either direction will result in the scrapers acting 20 upon the convex surfaces of adjacent disks as explained earlier.

A hand lever 20 on the rock-shaft serves to impart movement thereto and may be set in a desired fixed position by any usual or 25 well known latch arrangement 21, this being sufficiently well known to require no detailed drawing thereof.

In assembling the scrapers upon the implement their arms 16 may be adjusted to 30 proper positions on the bars 17 to the end that the scrapers will have the proper relation to their respective disks and so that, when the lever 20 is fixed by the latch mechanism mentioned, they will have the desired 35 yielding contact under all conditions.

In Figures 11 and 12 is shown a modified form of scraper operating mechanism wherein 40 21' is a hand-lever suitably pivoted at 22 on the tongue 2, for example. One end of the lever is made flexible by twisting a flat portion 23 in a vertical plane so as to lie perpendicularly to stresses to be placed upon it to be understood later. This end of said lever is pivoted to one end of a short lever 45 24 pivoted between its ends at 25 on the said tongue. At 26 is a similar short lever also pivoted between its ends on the tongue at 27. This is spaced from the lever 24, and an intermediate lever 28 is pivoted at its middle 50 and has pivotal connection at its ends with adjacent ends of the short levers as shown. In the present instance each of the bars 17 that control the scrapers is attached to one of the ends of the two levers 24 and 26. It 55 will be seen that the lever system is such that when the hand lever 21' is moved toward the right, Figure 11, the short lever 24 will be swung toward the left at its forward end and toward the right at its rear end. This action 60 shifts the bars 17 of that lever in oppo-

site directions and carrying the scrapers of the front pair of gangs toward the concave sides of the disks of those gangs.

Due to the connection of the lever 28, the rear short lever 26 will be swung on its pivot 70 in the same way, it being noted that the rear bars 17 are in positions opposite those of the front bars so that as shown by the arrows both said rear bars are shifted outwardly whereas the front ones are drawn inwardly 75 or toward the tongue which must result from the fact that the front and rear gangs are reversed as to the positions of their disks.

Though not illustrated, it is clear that there must be sufficient freedom of the pivot 80 points of the levers where they connect with one another to permit those points to move in arcs described from the pivots of said levers.

A quadrant or sector 29 is provided for 85 the lever 21' and any usual latch mechanism 30 is employed whereby the said lever 21' may be fixed in a given or desired position. Flexibility between the lever 21' and the mechanism operated by that member permits 90 the scrapers to yield to accommodate themselves to the condition of adhering matter on the disks or in case obstructions should pass between the disks and said scrapers. The lever 21' made flexible, or 95 any equivalent thereof, may be used in lieu of the arms 16 or in connection therewith.

This form of mechanism admits of operating all of the scrapers in their proper directions to a greater or less extent, as may 100 be desired, simultaneously with a single adjustment of the lever 21' as differing from the type first described.

I claim:

1. The combination with a harrow having 105 a rotary harrow disk, of a scraper blade pivotally mounted on said harrow and movable into and out of engagement with said disk, said blade being curved and having a scraping edge disposed at an angle with respect to the pivotal axis of said blade, and means for 110 swinging said blade to engage said scraping edge with said disk at an angle with respect to a radius of said disk, said scraping edge at one end first engaging said disk and then progressively engaging at its entire edge 115 therewith as it reaches an oblique position with respect to the radius of said disk.

2. The combination with a harrow having 120 a rotary harrow disk, of a scraper blade pivotally mounted on said harrow and movable into and out of engagement with said disk, said blade being curved and having a scraping edge disposed at an angle with respect to the pivotal axis of said blade as 125 viewed in two different planes, and means for swinging said blade to engage said scraping edge with said disk at an angle with respect to a radius of said disk, said scraping edge at one end first engaging said 130

disk and then progressively engaging at its entire edge therewith as it reaches an oblique position with respect to the radius of said disk.

5. 3. The combination with a harrow having a rotary harrow disk, of a scraper blade pivotally mounted on said harrow and movable into and out of engagement with said disk, said blade having a substantially spirally 10 curved scraping edge disposed at an angle with respect to the pivotal axis of said blade as viewed in planes at right angles to each other, and means for swinging said blade to engage said scraping edge at substantially 15 right angles to the surface of the disk to be scraped and at an angle with respect to a radius of said disk, said scraping edge at one end first engaging said disk and then progressively engaging at its entire edge 20 therewith as it reaches an oblique position with respect to the radius of said disk.

4. The combination with a harrow having a plurality of rotary harrow disks, of scraper blades pivotally mounted between 25 pairs of adjacent disks, each of said blades being curved and movable into and out of engagement with the convex and concave surfaces of adjacent disks, each scraping blade being curved and having a scraping 30 edge disposed at an angle with respect to

the pivotal axis of said blade, and means for swinging a plurality of said blades simultaneously to engage the convex surfaces or the concave surfaces of said disks, said blades being adapted to engage the concave 35 surfaces of said disks each with its scraping edge at any angle with respect to a radius of a disk, the scraping edge of each scraper at one end first engaging its respective disk and then progressively engaging at its entire edge therewith as it reaches an oblique 40 position with respect to the radius of said disk.

5. The combination in a harrow comprising 45 a main frame and two pairs of opposed gangs of harrowing disks, of a series of scraper-blades for each said gang of disks journaled in the frame, each blade including an arm, a separate member for all of the scrapers of a gang, all of the arms of a 50 gang of scrapers being connected to a member, and a common operating rod operatively connected to the several members, the relation of the said rod and members being such that certain of the blades are selectively 55 operated to the exclusion of others in a given movement.

In testimony whereof I affix my signature.

JOHN H. FLATLEY.
